No. 820,946.

PATENTED MAY 22, 1906.

A. M. BALZER.
LIFTER FOR MOLDED BUILDING BLOCKS.
APPLICATION FILED JUNE 24, 1905.

UNITED STATES PATENT OFFICE.

ANDREW M. BALZER, OF DES MOINES, IOWA, ASSIGNOR TO MIRACLE
PRESSED STONE COMPANY, OF SIOUX FALLS, SOUTH DAKOTA, A
CORPORATION OF SOUTH DAKOTA.

LIFTER FOR MOLDED BUILDING-BLOCKS.

No. 820,946.

Specification of Letters Patent.

Patented May 22, 1906.

Application filed June 24, 1905. Serial No. 266,762.

To all whom it may concern:

Be it known that I, ANDREW M. BALZER, a citizen of the United States, residing at Des Moines, in the county of Polk and State of 5 Iowa, have invented new and useful Improvements in Lifters for Molded Building-Blocks, of which the following is a specification.

The purpose of this invention is to provide a convenient device for handling molded tile 10 or concrete building-blocks for setting them in the wall to avoid the danger of breaking them in handling and to increase the rate at which they may be set.

It consists of the features of construction 15 set out in the claims.

In the drawings, Figure 1 is a plan view of a device embodying this invention. Fig. 2 is a side elevation, partly broken away and partly sectional, section being made in line 20 with one of the lever-receiving apertures in the fulcrum-plate, the device being shown in connection with a block to which it is adjusted for lifting. Fig. 3 is a transverse section at the line 3 3 on Fig. 2. Fig. 4 is a vertical transverse section through the device in line 25 with the central lifting-handle.

This lifter comprises a frame or supporting plate 1, to which there are pivoted levers 2 2 in pairs, the two of each pair being fulcrumed 30 upon the plate symmetrically disposed with respect to the longitudinal middle line, preferably near the lateral longitudinal margins of the plate, and the plate has apertures 3 3, through which the levers extend. Each lever has an arm 2^a, which extends approximately horizontally when the other arm is vertical, said horizontal arms of the two levers of each pair extending from opposite sides transversely of the plate and alongside 35 each other, projecting past the lateral margin of the plate opposite that near which the lever is fulcrumed. About midway of the length of the plate on upstanding lugs 1^a there are fulcrumed lifting-levers, each consisting of two side bars 5 and suitable spacing-bars, one of which forms a handle 5^a. The projecting ends of the arms 2^a of the levers 2 overhang the edges of the side bars of the levers 5 5, respectively, so that when said levers 5 are lifted at their outer ends by means

of the handles 5^a the levers 2 are rocked on their fulcrums, carrying the lower ends of the two levers of each pair inward toward each other. By said lower ends of said levers there are pivotally carried gripping shoes or 55 jaws 6 6, having their proximate faces suitably formed to grasp between them the web of a tile or building-block for lifting the block. This device is designed to be made of suitable dimensions to adapt it to handle blocks of known or standard dimensions and having the air-spaces between which are webs or dia-phragms to be grasped by the shoes 6 6, located at standard distances apart, and the two pairs of levers and their shoes 6 6 are 60 mounted on the frame or plate 1 so that they respectively enter the air spaces or cavities of the block. A loop handle or bail 7 is provided at the middle of the length of the plate 1, by which the whole device may be lifted 65 without operating the levers. Being thus lifted, it may be lodged upon a block with the gripping shoes or jaws 6 6 intruding properly into the air-spaces at opposite sides of the web or webs to be grasped, and the operator 70 then taking hold of the handles 5^a 5^a of the two oppositely-extending levers 5 5 and lifting them will first cause the gripping shoes or jaws of each pair to be advanced toward each other and to grasp the webs between them, 75 and when the shoes are thus stopped by the web the operator continuing to lift the handles 5^a will lift the block bodily instead of merely operating the jaws. When the block is lodged in position, the handles 5^a being released and the levers 5 being outspread, as in Fig. 1, the device may be picked up by the handle 7 without lifting the block.

I claim—

1. In a device for the purpose indicated, in 90 combination with a fulcrum-plate, a pair of levers fulcrumed on such plate projecting downwardly from their fulcrums, having arms extending in opposite directions in the plane of movement of the respective levers 95 about their fulcrums; a third lever fulcrumed on the plate for movement transversely with respect to said arms and extending under the same, and means by which the downwardly-extending levers grasp the block to be lifted. 100

2. In a device for the purpose indicated, in combination with a fulcrum-plate, a pair of levers fulcrumed thereon extending downwardly from their respective fulcrums, having each an arm extending toward the other lever of the pair in the plane of rocking movement of the levers; gripping-shoes pivotally carried by the said levers at their lower ends, and a third lever fulcrumed for movement transversely of said oppositely-extending arms of the first levers under the same. 65
3. In a device for the purpose indicated, in combination with the fulcrum-plate, a plurality of pairs of levers fulcrumed on the plate and extending downwardly from their respective fulcrums, the two levers of each pair having arms extending transversely, each toward the opposite lever of the pair, and two additional levers fulcrumed on the plate extending longitudinally transversely to said oppositely-extending arms of the first-mentioned levers under the same. 70
4. In a device for the purpose indicated, in combination with the fulcrum-plate, a pair of levers fulcrumed on the plate and extending downwardly from their fulcrums opposite each other and provided with means at their lower ends for gripping the block between them; an arm extending transversely across the interval between the levers; a third lever fulcrumed on the plate extending longitudinally transversely to said arms under the same, and a handle independent of said levers for lifting the fulcrum-plate. 75
5. In a device for the purpose indicated, in combination with a fulcrum-plate, a pair of levers fulcrumed on the plate and extending downwardly from their fulcrums, the two levers of each pair having means at their lower ends for gripping a block between them, and having at their upper ends arms extending each toward the opposite lever across the interval between them, and two lifting-levers fulcrumed on the plate extending transversely with respect to the arms of the first-mentioned levers of said pairs, respectively, under the same. 80
6. In a device for the purpose indicated, in combination with the fulcrum-plate, two pairs of levers fulcrumed on the plate and extending downwardly therefrom, and gripping-shoes pivotally mounted on said levers respectively, at their lower ends, said levers having at their upper ends arms extending transversely, each toward the opposite lever of the pair, the two arms of each pair of levers standing alongside each other and projecting each past the opposite lever; two additional levers fulcrumed on the plate and extending longitudinally thereof, comprising each two side bars which extend under the projecting ends of said transversely-extending arms of the first-mentioned levers, and a handle independent of said levers for lifting the plate. 85
7. In a device for the purpose indicated, in combination with a fulcrum-plate, a pair of levers fulcrumed on the plate and having each an arm projecting downward and moving toward and away from each other as the levers are rocked, a lever having its fulcrum carried by the plate and provided with a lifting-handle, said last-mentioned lever operating on the other arms of the first-mentioned levers to rock the downwardly-extending arms of said first-mentioned levers toward each other in the lifting movement of the last-mentioned lever, and means by which said downwardly-extending arms grip the block between them. 90
8. In a device for the purpose indicated, in combination with the fulcrum-plate, a pair of bell-crank levers fulcrumed on the plate having downwardly-projecting arms extending below the plate and horizontally-extending arms above the plate; means connected with the plate extending under said horizontally-extending arms for lifting the latter to move the downwardly-extending arms toward each other, and means by which said downwardly-extending arms grip the block between them when thus moved. 95
9. In a device for the purpose indicated, in combination with the fulcrum-plate, a pair of levers fulcrumed on the plate for rocking in parallel planes, having each a downwardly-projecting arm and an arm extending toward the other lever of the pair; a hand-operated lifting-lever fulcrumed on the plate operating by its upward movement on said last-mentioned arms, and means by which the downwardly-extending arms grip the block between them. 100
10. In a device for the purpose indicated, in combination with the fulcrum-plate, a pair of levers fulcrumed on the plate for rocking in parallel planes, having each a downwardly-projecting arm and an arm extending toward the other lever of the pair; means mounted on the plate engaging under said last-mentioned arms for lifting the same; means by which the downwardly-extending arms grip the block between them, and a handle independent of said levers for lifting the fulcrum-plate. 105
11. In a device for the purpose indicated, in combination with a fulcrum-plate, two pairs of levers fulcrumed on the plate for rocking in parallel planes, having each an arm projecting downward and an arm projecting toward the opposite lever of the pair; lifting-levers mounted on the plate engaging under the last-mentioned arms of the paired levers, and means on the downwardly-extending arms of said paired levers for engaging the block between the two levers of each pair. 110
- 120
- 125

12. In a device for the purpose indicated, a fulcrum-plate, gripping-shoes connected therewith, and a lever having a fulcrum connection with said plate, and means by which said lever actuates the shoes for gripping when operated for lifting the plate.

In testimony whereof I have hereunto set

my hand, in the presence of two witnesses, at Des Moines, Iowa, this 5th day of June, A. D. 1905.

ANDREW M. BALZER.
